UNITED STATES PATENT OFFICE.

THOMAS C. SHEEHAN, OF CALDWELL, NEW JERSEY, ASSIGNOR TO DURHAM DUPLEX RAZOR COMPANY, OF NEW YORK, N. Y., A CORPORATION OF NEW YORK.

RAZOR.

1,088,183.

Specification of Letters Patent. Patented Feb. 24, 1914.

Application filed May 15, 1912. Serial No. 697,402.

To all whom it may concern:

Be it known that I, THOMAS C. SHEEHAN, a citizen of the United States, residing at Caldwell, county of Essex, and State of New Jersey, have invented a new and useful Improvement in Razors, of which the following is a specification.

This invention relates to an improvement in razors, particularly to the type known in trade as the Durham.

The main object of the present invention is the production of an improved razor of the above type in which a blade is directly held in contact with a support by simple means carried by the support and engaging the blade itself, said means being also capable of preventing accidental displacement of the blade.

Another object is to lessen the cost of manufacturing, so that an efficient razor can be made and sold at a lower price than has heretofore been possible.

With these and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Figure 1 is a general view of a device constructed in accordance with the invention, Fig. 2 is an enlarged sectional view taken on the line 2-2 in Fig. 1, and Fig. 3 is an enlarged cross-sectional view taken on the line 3-3 in Fig. 1.

In carrying the invention into effect, there is provided a handle 1 to which is pivoted a shank 2 extending from what may be termed a blade supporting member 3. This blade supporting member is in the form of a double guard, but it is to be understood that, in certain constructions, the support need not be a guard. There is further provided a blade 4 of substantial thickness and rigidity; and means are provided for holding the blade upon the support. In the device selected to illustrate the invention, this holding means consists of a pair of lugs 5, each offset from the main body of the support 3. The operating faces of these lugs lie in a plane substantially parallel with the surface of the supporting member 3, and each is provided with a projection 6 adapted to en-

gage an indentation 7 formed upon the face of a ledge 8, which ledge is countersunk from one face of the blade adjacent a perforation 9 extending through the blade. To attach the blade to the support, the lugs 5 are first passed through the perforation 9, and then slid longitudinally along the ledges 8 until the projections 6 snap into the indentations 7. Detachment of the blade from the support is of course effected by a reverse operation. It will be noted that the lugs 5 lie between the outer surfaces or non-contacting sides of the support 3 and the blade 4.

While, in certain constructions, the cutting edges of the blade may be centrally located with respect to the flat faces of the blade; as shown, each of the cutting edges is formed by a short bevel 10 and a long bevel 11, the short bevel 10 being on the side next the guard, and the long bevel 11 being on the same side as the countersunk ledges.

As shown, the perforations 9 are unsymmetrically arranged with respect to the ends of the blade. This is to prevent assembling of the blade and support with the long bevels 11 next the support. When the blade is ground to bring the cutting edges thereof in a plane midway between the sides of the blade, the perforations need not be so arranged.

Changes and variations may be made in the structure by means of which the invention is carried into effect. This invention therefore is not to be restricted to the precise details of the structure shown and described.

What is claimed:

1. In a razor, the combination with a blade having a pair of slots each slot having a countersunk ledge adjacent said slot, of a handle, and a shank pivoted to the handle and provided with an integral guard having a pair of integral lugs offset from said guard and adapted to pass through the slots and engage the ledges of the blade to hold the blade and guard together.

2. In a razor, the combination with a blade having a pair of slots unsymmetrically arranged with respect to the ends of the blade each slot having a countersunk ledge adjacent said slot, said blade having two opposite cutting edges each formed by a long and a short bevel the long bevels being on the same side of the blade as the ledges,

of a handle, and a shank pivoted to the handle and provided with an integral guard having a pair of integral lugs offset from said guard and adapted to pass through the slots and engage the ledges of the blade to hold the blade and guard together.

In testimony whereof, I have signed my

name to this specification in the presence of two subscribing witnesses.

THOMAS C. SHEEHAN.
